ATTACHING DEVICE

Warren McArthur, Bantam, Conn., assignor, by
mesne assignments, to Reconstruction Finance
Corporation, New York, N. Y., a corporation of
the United States

Application September 15, 1944, Serial No. 554,284

5 Claims. (Cl. 24—223)

1

This invention relates to an attaching device, and in its more specific aspects, to an attaching device that is adapted to be removably secured to a member.

An object of this invention is the provision of a device that may be readily attached to and subsequently detached from a member, such as the floor, wall or ceiling of a vehicle without the use of tools.

Another object of this invention is to provide a device of the character indicated that is adapted to be used with cables, ropes, hooks or the like in maintaining merchandise in predetermined regions within a vehicle.

It is a further object of this invention to provide a removable attaching device that remains in attached position and does not become disengaged upon being subjected to jars, vibrations or impacts.

A still further object of the invention is to provide a relatively lightweight inexpensive attaching device that is simple and sturdy in construction.

The device of this invention is in the nature of a securing means that may be readily and positively placed in engagement with a suitable opening in the floor, wall or ceiling of a vehicle and that is provided with a means adapted to engage a rope, cable and the like for fastening cargo within the vehicle. The opening in which my device is removably disposed is preferably in the form of a bayonet slot. One or more bayonet slots may be provided in the floor, wall or ceiling of the vehicle or may be provided in plates secured in or to such floors, walls or ceilings.

These, as well as other objects, together with the advantages obtainable by the practice of this invention, will be apparent upon reference to the following detailed description and accompanying drawings which pertain to a preferred embodiment of the invention.

In the drawings:

Figure 1 is a top plan view of the device of this invention attached to a member such as a plate;

Figure 2 is a vertical cross-sectional view taken along line 2—2 of Figure 1;

Figure 3 is a view similar to Figure 2 illustrating another relative position of the parts;

Figure 4 is a top plan view of a member and depicting a bayonet slot extending therethrough; and

Figure 5 is a view of the attaching device in side elevation.

Reference is now had to the drawing wherein like numerals indicate corresponding parts in the

several views. For the purpose of describing the invention, I have illustrated a member 10 which may be in the nature of a plate having a bayonet slot 11 extending therethrough. The bayonet slot preferably comprises an enlarged arcuate portion 12 and a portion 13 of reduced width. Plate 10 is adapted to be secured in a suitable opening provided in the floor, wall or ceiling of a vehicle or other type of structure by means of screws (not shown) passing through apertures 14. It is to be understood that bayonet slot 11 may, if desired, be formed directly in a floor, wall or the like as desired.

Base plate 15 is provided with an opening 16. A post 17 extends through opening 16 and is affixed to base plate 15 by soldering or in any other way known to the art. It will be observed that a portion of post 17 projects above the upper face surface of base plate 15 while another portion projects below the lower face surface of the base plate. The upper portion of post 17 is provided with an arcuate passage to pivotally receive a connector or ring 19. The lower portion of post 17 is formed with a lock head 20 and an annular groove or recess 21. Recess 21 is adapted to register with portion 13 of the bayonet slot as shown in Figure 2.

Base plate 15 is provided with a second opening 22. A hollow and preferably cylindrical casing 23 is open at its lower end and is provided with a wall 24 having a passage 25 at its upper end. The lower end of casing 23 is disposed in opening 22 and is attached to the base plate by soldering or otherwise. A plunger or piston 26 is reciprocable in casing 23 and carries an upwardly projecting rod 27 that extends through opening 25 in wall 24. A compression spring 28 concentric with rod 27 is positioned within casing 23 and bears against the upper end of plunger 26 and end wall 24 to normally urge plunger 26 in a downward direction.

A knob 29 embraces the upper end of rod 27 and is secured thereto by a pin 30. As is best shown in Figure 2, the lower end of knob 29 abuts wall 24 to limit downward movement of rod 27 and plunger 26. Knob 29 may be manually operated to move rod 27 and plunger 26 upwardly against the action of spring 28 to the position shown in Figure 3.

Base plate 15 and the equipment connected thereto may be readily attached to and subsequently detached from member 10 by a procedure that will now be briefly described. Lock head 20 of post 17 is inserted in enlarged portion 12 of the bayonet slot and plunger 26 is moved up-

wardly in casing 23 to the position shown in Figure 3. Base plate 15 is then slid along the upper surface of member 10 until recess 21 registers with portion 13 of the bayonet slot. Base plate 15 is then moved along the upper face surface of member 10 until plunger 26 registers with portion 12 of the bayonet slot, at which time the plunger is urged into said portion 12 by spring 28, thereby effecting locking engagement.

In order to detach post 17 from member 10, knob 29 is manually operated against the action of spring 28 to move plunger 26 upwardly and out of portion 12 of the bayonet slot. The base plate is then slid along member 10 until post 17 is in the position shown in Figure 3, at which time lock head 29 may be withdrawn through portion 12 of the bayonet slot.

Based on the foregoing, it is believed that the objects, advantages and construction of my instant invention will be readily apparent to persons skilled in the art. It is to be borne in mind, however, that various changes in the apparatus herewith illustrated and described may be resorted to without departing from the spirit of this invention or the scope of the subjoined claims.

I claim:

1. In a device of the character described, a first unit comprising a member having a bayonet slot extending therethrough, a second unit comprising a base, a post connected to the base and including a head portion, said post having a recess formed therein intermediate the head portion and the base and registering with the bayonet slot in the region of the recess, a plunger movable through the base in one direction and registering with the bayonet slot when the units are in normal engagement, and means for moving the plunger in the opposite direction to remove the plunger from the bayonet slot when effecting disengagement between the units.

2. In a device of the character described, a first unit comprising a member having a bayonet slot extending therethrough, a second unit comprising a base, a post connected to the base and including a head portion, said post having a recess formed therein intermediate the head portion and the base and registering with the bayonet slot in the region of the recess, a plunger movable through the base in one direction and registering with the bayonet slot when the units are in normal engagement, resilient means urging the plunger through the base in said one direction, and means for moving the plunger in the opposite direction against the action of the resilient means to remove the plunger from the bayonet slot when effecting disengagement between the units.

3. In a device of the character described, a first unit comprising a member having a bayonet slot extending therethrough, a second unit comprising a base, a post connected to the base and including a head portion, said post having a recess formed therein intermediate the head portion and the base and registering with the bayonet

slot in the region of the recess, a plunger movable through the base in one direction and registering with the bayonet slot when the units are in normal engagement, means for moving the plunger in the opposite direction to remove the plunger from the bayonet slot when effecting disengagement between the units, and means independent of the post for limiting movement of the plunger with respect to the base in said one direction.

4. In a device of the character described, a first unit comprising a member having a bayonet slot extending therethrough, a second unit comprising a base having an upper face surface and a lower face surface, a post carried by the base, a first portion of the post projecting above said upper face surface and a second portion of the post projecting below said lower face surface, a connector pivotally coupled to said first portion, said post being recessed in said second portion and registering with the bayonet slot in the region of the recess, a plunger carried by the base, resilient means for moving the plunger downwardly through the base and beyond said lower face surface to effect registration between the plunger and the bayonet slot when the units are in normal engagement, and means for moving the plunger upwardly through the base to remove the plunger from the bayonet slot when effecting disengagement between the units.

5. In a device of the character described, a first unit comprising a member having a bayonet slot extending therethrough, a second unit comprising a base having an upper face surface and a lower face surface, a post carried by the base, a first portion of the post projecting above said upper face surface and a second portion of the post projecting below said lower face surface, a connector pivotally coupled to said first portion, said post being recessed in said second portion and registering with the bayonet slot in the region of the recess, a plunger carried by the base, resilient means for moving the plunger downwardly through the base and beyond said lower face surface to effect registration between the plunger and the bayonet slot when the units are in normal engagement, means independent of the post for limiting said downward movement of the plunger, and means operable from above the base for moving the plunger upwardly through the base to remove the plunger from the bayonet slot when effecting disengagement between the units.
